UNITED STATES PATENT OFFICE

HERMANN RIËSS, OF BERLIN-SCHONEBERG, GERMANY

PRESSURE FLUID GENERATOR

Application filed October 18, 1926, Serial No. 142,457, and in Germany October 20, 1925.

This invention relates to pressure fluid generators in which the gas-steam which serves as pressure fluid is generated and both constituents are intimately mixed.

Generators of this type which have become known till now have the inconvenience that the steam designed for mixing with the gases from explosion must either be generated in a separate plant or, if it is generated in a water jacket which surrounds the explosion chamber, a sufficient quantity of steam is at disposal only after the engine has worked for a relatively long period. Up to that time however the engine will already have been heated very strongly. In both cases it is therefore impossible to utilize gas-steam internal combustion engines.

The construction of the present invention is such that it is possible to generate in the engine a sufficient quantity of steam at the first explosion and to maintain the temperature of the driving fluid from the beginning at so low a degree, that the utilization of explosion engines of this type becomes possible also for motor cars, aircraft and the like.

This object is attained according to the present invention by arranging the injector in a special chamber, and by winding around the nozzles of this injector tubes in spiral shape which terminate in a ring shaped tube located in an evaporating cup and having discharge openings, fresh water or water of condensation from the engine being fed to said spiral shaped tubes. The fresh water or water of condensation which flows through these spiral shaped tubes is heated upon the first explosion to such a high temperature, that it is transformed into steam upon the evaporating cup which is also strongly heated, said steam being instantaneously admixed with the explosive gases by the suction effect of said gases.

Figure 1 of the accompanying drawing shows in a diagrammatical sectional view one form of construction of the gas-steam generator,

Fig. 2 is a sectional view on the line 2—2 of Fig. 1, and

Fig. 3 is a perspective view of the steam

chamber, a part of the chamber being broken away.

The apparatus consists essentially of an explosion chamber 1 for the production of a gas jet, and of a steam chamber 2. The explosive mixture of air and gas is supplied under pressure to the explosion chamber 1 by the usual means through an inlet valve 3. A sparking plug or similar igniting device 4 serves for the ignition. The residues are exhausted from the combustion chamber through an outlet valve 5. The explosion chamber is held closed up to the ignition by a disk valve 6, the rod 7 of which is controlled by a pressure spring 8 arranged on the outside of the chamber 1, said spring being of such a strength that the valve will not be opened by the charging pressure. The stroke of the valve 6 takes place in a nozzle tube 9 which extends into a nozzle tube 10 of the steam chamber 2. These two nozzle tubes form an injector.

The steam chamber is supplied with steam from any suitable source. In the form of construction, shown by way of example, however the cooling water jacket 11 of the explosion chamber 1 is used as steam generator. With this object in view the jacket 11 has a steam dome 12, which is connected to the steam chamber 2 by means of a pipe 13. In this pipe 13 a check valve 14 is arranged. A tubular socket 15 serves to replace in the jacket 11 the water which has been evaporated. In order to evaporate instantaneously water which might have been carried over into the steam chamber 2 the steam pipe 13 is connected with a ring-shaped steam tube 16 which has tubular outlets 17 downwardly directed towards a vaporizing plate 18 which is arranged under the ring-shaped tube 16 and which is fixed on a vertical bracket 19 carried by the nozzle 10. The bracket 19 consists of metal having heat conductive properties so that the burnt gases from the nozzle 10 will heat the plate 18 in order that the steam from the openings 24 will be more effectively vaporized.

Around the nozzles 9 and 10 tubes 20, 21 of a material which is a good conductor of heat, for instance copper, are wound in spiral

shape to which tubes, by means of a pump not shown and through a common supply pipe 22, fresh water or water of condensation from the engine is fed, said tubes 20, 21 ending both in a horizontal tube 23 which has discharging openings 24 located within the cup-shaped vaporizing plate 18. This arrangement serves specially for the rapid generating of steam already beginning at the first explosion shock.

To the mixing nozzle 10 a pipe 25 is connected, which ends in an accumulating and pressure equalizing chamber 26, a check valve 27 being arranged in said pipe. To the chamber 26 the supply pipe for the engine is connected.

Any approved means may be employed for actuating the valves 3 and 5 and for timing the spark of the plug 4, and for also supplying the combustion chamber 1 with a mixture of fuel and air. The means as shown includes a motor p which drives the shaft b' in order that the cam e thereon will actuate the stem of the valve 3. This shaft has thereon a beveled gear d' meshing with the gear d on the vertical shaft b , the latter shaft being provided with an eccentric e for controlling the movement of the valve 5 and likewise the distributor h for timing the spark of the plug 4. While the means above described are preferable, it will of course be understood that other conventional means may be utilized if desired, for instance, the construction in the patent to Hess, No. 582,351, May 11th, 1897, may be adapted with slight modifications for this purpose.

Fuel is injected into the air pipe o through the pipe n , the entrance of the fuel into the chamber 1 being controlled by the valve 3, as is customary.

The valve 6 serves to retain the steam gas mixture within the explosion chamber 1 until the same is ignited. It is obvious that the valve 6 will be opened by the high pressure within the explosion chamber, such pressure overcoming the resistance of the spring 8, and by this means permits the passage of the gases from the explosion chamber 1 through the opening 2'. The valve 6 remains open until almost the entire quantity of the burnt gases have passed out of the explosion chamber and have passed through the nozzle 10 in a direction toward the collecting vessel 26, mixing with steam in the chamber 2. As soon as the force of the explosion has come to an end, the spring 8 causes the valve 6 to close the opening 2'.

The apparatus operates as follows:—To the explosion chamber 1 an explosive gas-air mixture is supplied through the valve 3 with the aid of a charge pump (not shown), said mixture being ignited by the sparking plug 4. The increase of pressure due to the explosion opens the valve 6 and the gases from explosion rush through the injector nozzle 9

into the suction nozzle 10 of the steam chamber 2, causing at the same time a rapid heating of the two nozzles 9 and 10 as well as of the serpentine tubes 20, 21 closely surrounding said nozzles. The fresh water or water of condensation which flows through these serpentine tubes consequently is transformed into steam which, flowing out through the discharging openings 24 of the tube 23, strikes onto the evaporating cup 18, which in the meantime has also been strongly heated, so that the evaporating process is effectively completed if this should yet be necessary.

The cup-shaped vaporizing plate 18 is rigidly connected by the bracket 19 to the highly heated mixing nozzle 10 and is also highly heated by direct conduction of heat.

The pipe 22 leading to the steam generator 20, 21 is cut off as soon as the jacket 11 is able to produce sufficient steam.

The steam generated in this manner immediately enters the steam chamber 2, but is carried along by the suction effect of the gases from explosion flowing through the nozzles 9 and 10, so that a homogenous mixture of steam and gas is produced, a complete equalization of temperature between both these media taking place. In the manner which has just been described a sufficient quantity of steam is already generated during the first explosion shock, this steam being admixed immediately with the gases from explosion.

The valve 6 remains open until the gases from explosion have expanded to the charging pressure. As soon as the valve has closed again the exhaust valve 5 opens in order that the explosion chamber be freed from residue gases and ready to receive a new charge.

The proceeding which has just been described is repeated until the water jacket 11 which surrounds the explosion chamber 1 has been sufficiently heated to supply continuously the quantity of steam which is necessary for the production of the gas-steam. Owing to the high temperature of the gases from explosion, the steam which is generated in the serpentine tubes 20, 21 or in the water jacket 11 is so strongly heated and the temperature of the mixture is at the same time lowered so much that it can no more exert any prejudicial action upon the engine. The pressure increase occurring in the steam chamber 2 cannot back up in the steam dome 12 owing to the check valve 14.

The mixture of gases from explosion and steam flows through the pipe 25 into the accumulator chamber 26, in which the fluctuations of pressure of the driving mixture are equalized in such a manner that the driving mixture which passes to the engine will flow off at approximately uniform pressure and uniform speed.

Having now particularly described and as-

certained the nature of my said invention, I declare that what I claim is:—

A gas steam generator comprising an explosion chamber, means for supplying fuel to said chamber, means for igniting the fuel, a water jacket surrounding said explosion chamber, a steam dome thereon, a steam chamber, an injector in said steam chamber communicating with said explosion chamber, 10 a normally closed valve cooperative with said injector adapted to be opened by the pressure of the ignited gases, conduit means communicating said steam dome with said steam chamber, a check valve in said conduit, a 15 plurality of spirally wound tubes around the nozzles of said injector, means for supplying the tubes with water, a vaporizing plate supported in the steam chamber, a tube having discharge openings disposed above said 20 plate and communicating with said spirally wound tubes, a discharge tube in said steam chamber disposed above said plate communicating with the conduit means of said steam dome, and outlet means in said steam chamber having a check valve associated therewith.

In testimony whereof I have hereunto set my hand.

HERMANN RIËSS.
